gesellschaft Brown, Boveri & Cie., Baden, Swit-
zerland, a joint-stock company of Switzerland

Application November 25, 1933, Serial No. 699,660
In Germany December 17, 1932

19 Claims. (Cl. 175—363)

This invention relates in general to the control of electric current converting systems employing electron discharge devices and more particularly to voltage regulating means for a plurality of converting units in series connection.

Electron discharge devices are frequently utilized in electric current converting systems such as rectifying, inverting, frequency changing and direct current voltage converting systems. When a system of the above character is to operate directly at very high voltages there is a danger of faulty operation of the electron discharge device, and it is therefore frequently preferred to utilize a plurality of converting units connected in series instead of a single unit to reduce the danger of disturbances within the system. To regulate the output voltage of such a system over a considerable range it is then generally necessary to provide each converting unit with separate regulating means, thereby rendering the installation complicated and expensive. By controlling the operation of some of the converting units so as to cause such units to operate alternately in conjunction with and in opposition to the remaining units, the voltage of the system may be regulated by simpler and less expensive means. Some of the units then transmit energy in one direction or the other units may retransmit a portion of such energy in the opposite direction.

It is therefore among the objects of the present invention to provide a current converting system employing a plurality of serially connected electron discharge devices in which energy may be transmitted simultaneously in both directions of flow.

Another object of the present invention is to provide a current converting system employing a plurality of serially connected electron discharge devices in which some of the devices transfer energy in one direction from a source and other devices may return a portion of such energy to the source.

Another object of the present invention is to provide a current converting system employing a plurality of serially connected electron discharge devices in which the output voltages of some of the devices may oppose the output voltages of the other devices.

Another object of the present invention is to provide a current converting system employing a plurality of serially connected electron discharge devices in which the output voltages of some of the devices may be reversed.

Objects and advantages other than those above

set forth will be apparent from the following description when read in connection with the accompanying drawing in which the figure diagrammatically illustrates a rectifying-inverting system comprising two series connected electron discharge devices of which one may be regulated by means of control electrodes.

Referring more particularly to the drawing by characters of reference, reference numeral 6 designates an alternating current supply line energized at any desired voltage of any frequency and having any number of phases, herein represented as a three phase line. It is assumed that energy is to be converted between line 6 and a direct current line 7, 8. Line 6 is accordingly connected with the primary winding 9 of a transformer having a secondary winding 11 comprising a plurality of phase displaced portions connected in star to form a neutral point connected with conductor 7. The different phase portions of winding 11 are severally connected with the anodes 12 of a vapor type electron discharge device 13 having a cathode 14 and hereinafter designated as rectifier 13 for the sake of brevity.

Cathode 14 is connected with the neutral point of another secondary winding 16 in inductive relation either with winding 9 or with a separate winding 17 to form therewith a second transformer unit. Winding 17 may be energized from any suitable source of alternating current and is preferably connected with line 6, although it will be understood that the sources energizing windings 9 and 17 may be entirely independent. Although transformers 9, 11 and 16, 17 have been represented as being similar in their connections, such transformers may be connected in different manner and the voltages of windings 11 and 16 need not be in any particular relation except that the range of regulation obtainable is dependent upon such relation. The different portions of winding 16 are severally connected with the anodes 18 of a second rectifier 19 having a cathode 21 connected with conductor 8. Rectifiers 13 and 19 are thus operatively connected in series across line 7, 8 with a current smoothing reactor 22 connected in the line if so desired.

Windings 9 and 17 are preferably connected with line 6 through a circuit breaker 23 provided with sets of contacts for the connection of line 6 with the auxiliary circuits of rectifiers 13 and 19. The auxiliary contacts of circuit breaker 23 connect line 6 with the coil of a time delay relay 24 operable to connect line 6 with the ignition and excitation transformers 26 and 27 supplying

ignition and excitation currents to rectifiers 13 and 19. Rectifier 13 is provided with an ignition anode 28 and with excitation anodes 29 which are connected with transformer 26 in any suitable 5 well known manner to cause striking of an arc within rectifier 13 and continued excitation of such arc upon energization of transformer 26. Rectifier 19 is likewise provided with an ignition anode 31 and excitation anodes 32 connected with transformer 27.

Rectifier 19 is further provided with a plurality of control electrodes 33 severally controlling the attachment of the arc to the different anodes 18 of rectifier 19. Each control electrode 33 15 is connected through resistors as at 34 and 36 with the negative terminal of a suitable source of direct current such as a direct current generator 37. The negative terminal of generator 37 is also connected with cathode 21 through a resistor 38 and contacts 39 of a relay 41 while the positive terminal thereof is connected with cathode 21 through a second resistor 42. Resistors 38 and 42 thus constitute a voltage divider whereby the potentials of the terminals of generator 25 37 are maintained in invariable relation with the potential of cathode 21.

The shaft of generator 37 drives the brush 43 of a distributor 44 provided with a plurality of conductive segments. Alternate segments of distributor 44 are severally connected with the different control electrodes 33 through resistors 34, each segment also being connected with the adjacent idle segment through a capacitor 47 in parallel with a resistor 46. The capacitor is provided for the purpose of preventing arcing at the segments while the resistor permits discharge of the capacitor between successive revolutions of the brush 43. Brush 43 is connected with the positive terminal of generator 37 through contacts 48 of relay 41, the coil of which is energized from a current transformer 49 inserted in the connection between line 6 and windings 9 and 17. Operation of relay 41 in response to the magnitude of the current of current transformer 45 49 causes the connection of brush 43 with generator 37 to be opened and causes cathode 21 to be directly connected with the positive terminal of generator 37 through contacts 51 of relay 41. Current transformer 49 is short circuited by means of contacts 52 of circuit breaker 28 when the main contacts of such circuit breaker are open to avoid undesired operation of relay 41 in response to surges resulting from switching operations of circuit breaker 23.

Brush 43 and generator 37 are rotated at synchronous speed by means of a synchronous motor 53 having an armature 54 energized from line 6 and having a plurality of field windings 56, 57 and 58. Such field windings are short circuited 60 during starting operation of the motor through the contacts of a relay 59 which also controls the circuit of the shunt field winding of generator 37. The coil of relay 59 is connected in series with a rheostat 61 in the excitation circuit of rectifier 19, whereby rheostat 61 is energized with substantially uniform direct current, a portion of such current flowing through windings 56, 57 and 58 during synchronous operation of motor 53. Rheostat 61 is adjustable to permit obtaining any desired distribution of current between windings 56, 57 and 58 and therefore any desired angular relation between the field structure of the motor and the rotating magnetic field of the armature. A resistor 62 may be connected in 70 parallel with the coil of relay 59 and rheostat 61

to limit the voltage surges resulting therein from the operation of relay 59.

The operation of the system will now be considered assuming first that line 6 is energized and that line 7, 8 is to be energized at a voltage 5 gradually increasing from zero to the maximum value thereof. Closure of circuit breaker 23 causes transformers 9, 11 and 16, 17 to be energized. Armature 54 of motor 53 is then energized through the auxiliary contacts of circuit breaker 10 23. Windings 56, 57 and 58 being short circuited through the contacts of relay 59, motor 53 operates as an induction motor and reaches a speed closely approaching the synchronous speed thereof. After a predetermined time delay, relay 24 15 closes the contacts thereof to cause energization of transformers 26 and 27, whereby an arc is struck and is maintained in each of rectifiers 13 and 19 by the ignition and arc maintaining circuits operating in a well known manner. When 20 the flow of current through transformer 27 reaches the full value thereof, such current causes operation of relay 59 which removes the short circuit of windings 56, 57 and 58 and completes the circuit of the field winding of generator 37 25 thereby permitting self excitation of such generator. Motor 53 at that time is operating in synchronism with the voltage of line 6, the relative position of the field windings with respect to the rotating magnetic field of the motor being determined by the adjustment of rheostat 61.

The potentials of the terminals of generator 37 being fixed with respect to the potential of cathode 21 by means of resistors 38 and 42, control electrodes 33 receive, from the negative 35 terminal of generator 37, a potential which is negative with respect to the potential of cathode 21. Brush 43 then sequentially impresses, on the several control electrodes, a potential from generator 37 which is positive with respect to the 40 potential of cathode 21 to release the sequential flow of current through the anodes associated with the control electrodes.

At the time of closure of circuit breaker 23, rheostat 61 is adjusted in such manner that each 45 control electrode 33 is positively energized in the portion of the voltage cycle during which the associated anode receives a negative voltage from winding 16 to thereby introduce, in line 7, 8, a negative voltage opposing the positive voltage 50 introduced therein by rectifier 13 operating in the well known uncontrolled manner. If the negative voltage introduced by winding 16 and rectifier 19 is at least equal to the positive voltage introduced by winding 11 and rectifier 13, the 55 resulting voltage impressed on line 7, 8 is equal to zero or is even negative and line 7, 8 receives no current.

Movement of rheostat 61 in the one direction causes the field structure of motor 53 and brush 60 43 to be given an increasing lead with respect to the rotating magnetic field inducted by winding 54 to thereby advance the moment at which each control electrode is energized during the voltage cycle of line 6. The negative terminal voltage 65 of winding 16 and rectifier 19 then becomes lower, as is well known, and when such voltage is lower than the voltage of winding 11 and rectifier 13 a current flow is established from conductor 7 through rectifiers 13 and 19 to conductor 8. Such 70 current flow occurs at a voltage which is the difference of the average voltages of rectifier 13 and rectifier 19. During such operation rectifier 13 converts energy from line 6 to line 7, 8 while rectifier 19 acts as a direct current inverter to 75

return a portion of such energy from line 7, 8 to line 6. The balance of the energy is then utilized in current consuming devices (not shown) connected with line 7, 8. Continued movement 5 of rheostat 61 causes continued advance of the times of energization of the control electrodes and a gradual decrease of the voltage of rectifier 19 to zero. Line 7, 8 then receives energy only from rectifier 13, the flow of current through 10 rectifier 19 then occurring without transfer of energy between the two lines. The times of energization of control electrodes 33 may then be further advanced whereby the output voltage of rectifier 19 gradually increases positively from 15 zero, each control electrode then being positively energized when the associated anode receives a positive voltage from winding 16. Rectifier 19 then no longer operates as an inverter but cooperates with rectifier 13 in rectifying alternating 20 current received from line 6. The times of energization of control electrodes 33 may be advanced to such extent that each control electrode becomes positive when the associated anode becomes positive with respect to the anode carrying 25 current at the time considered. Rectifier 19 then delivers current at the maximum output voltage thereof and further advance of the times of energization of control electrodes 33 is without effect on the operation of the rectifier. The 30 voltage of line 7, 8 is then at a maximum value equal to the sum of the voltages of rectifiers 13 and 19.

By reversing the motion of rheostat 61 the voltage of line 7, 8 may be again reduced to 35 zero by first gradually reducing the voltage of rectifier 19 to zero and thereafter reversing and increasing the voltage of such rectifier. Further reverse movement of rheostat 61 will cause control electrodes 33 to become positive to release the flow of current through the associated anodes to thereby impress on line 7, 8 a negative voltage greater than the positive voltage of rectifier 13. If line 7, 8 is connected with 40 loads or with sources operable to impress thereon a reverse voltage, rectifier 19 may then receive energy from line 7, 8 and convert such energy into alternating current supplied to line 6, a portion of such energy being returned at 45 a lower voltage to line 7, 8 by means of rectifier 13.

When rectifier 19 is operated at a voltage opposing that of rectifier 13, a certain amount of energy is therefore circulated between the two rectifiers, thereby causing losses in the circuit 50 thereof. Such losses are, however, of reduced importance when compared to the advantage of simplification of the control system, especially when a large range of regulation is required only during short periods of time.

Upon occurrence of a disturbance such as a short circuit in line 7, 8, current transformer 49 energizes the coil of relay 41 with an increased amount of current and causes such relay to operate to disconnect brush 43 from generator 37.

Control electrodes 33 are then constantly maintained at a potential which is negative with respect to the potential of cathode 21 by the full amount of the voltage of generator 37 as a result of the opening of contacts 39 and closure of 65 contacts 51. The flow of current is thereby caused to be extinguished in rectifier 19 and therefore also in rectifier 13 and in line 7, 8.

From the above description of the operation of the system it will be apparent that serially connected rectifiers 13 and 19 are operable to cause 70

simultaneous transfer of energy in both directions between lines 6 and 7, 8. Line 7, 8 then receives energy from line 6 through rectifier 13, and rectifier 19 is operable to cause the flow of energy therethrough from line 7, 8 back to 5 line 6. The control means for rectifier 19 are operable to cause the voltage impressed by rectifier 19 on line 7, 8 to oppose the voltage impressed on such line by rectifier 13. The voltage of rectifier 19 may be regulated and reversed by 10 means of rheostat 61, motor 53, distributor 44 and control electrodes 33. Upon occurrence of abnormal conditions within the system the control electrodes of rectifier 19 are negatively energized to cause interruption of the flow of current 15 through both rectifiers.

Although but one embodiment of the present invention has been illustrated and described, it will be apparent to those skilled in the art that various changes and modifications may be made 20 therein without departing from the spirit of the invention or from the scope of the appended claims.

It is claimed and desired to secure by Letters Patent:

1. In an electric current converting system, an electric current line, a plurality of electron discharge devices serially connected across said line, a second electric current line connected with said devices, and means controlling one of said devices to cause simultaneous transfer of energy through said devices in both directions between said lines.

2. In an electric current converting system, an electric current line, a plurality of electron discharge devices serially connected across said line, a second electric current line connected with said devices and operable to supply current through one of said devices to the first said line, and means operable to control another of 40 said devices for causing flow of energy therethrough from the first said line to the second said line.

3. In an electric current converting system, an electric current line, a plurality of electron discharge devices serially connected across said line, a second electric current line connected with said devices for transferring energy therethrough to the first said line, and means operable to control one of said devices for causing flow of 50 energy therethrough from the first said line to the second said line.

4. In an electric current converting system, an electric current line, an electron discharge device, a second electron discharge device, means 55 for connecting said discharge devices with said line, a second electric current line, means for operatively connecting said devices serially across the second said line to cause transfer of energy from the first said line to the second said line, 60 and means controlling the second said discharge device operable to cause transfer of energy therethrough from the second said line to the first said line.

5. In an electric current converting system, an 65 electric current line, an electron discharge device, a second electron discharge device, means for connecting said discharge devices with said line, a second electric current line, means for operatively connecting said devices serially across 70 the second said line to cause impression of voltage thereon, and means controlling the second said discharge device and operable to cause the voltage impressed on the second said line by the second said discharge device to oppose the volt- 75

age impressed thereon by the first said discharge device.

6. In an electric current converting system, an electric current line, an electron discharge device, a second electron discharge device, means for connecting said discharge devices with said line, a second electric current line, means for operatively connecting said devices serially across the second said line to cause impression of voltage thereon, means controlling the second said discharge device and operable to cause the voltage impressed on the second said line by the second said discharge device to oppose the voltage impressed thereon by the first said discharge device, and means controlling the last said means to regulate the voltage impressed on the second said line by the second said discharge device.

5

10

15

20 7. In an electric current converting system, an electric current line, an electron discharge device, a second electron discharge device, means for connecting said discharge devices with said line, a second electric current line, means for operatively connecting said devices serially across the second said line to cause impression of voltage thereon, means controlling the second said discharge device and operable to cause the voltage impressed on the second said line by the second said discharge device to oppose the voltage impressed thereon by the first said discharge device, and means controlling the last said means to cause reversal of the voltage impressed on the second said line by the second said discharge device.

25

30

35 8. In an electric current converting system, an electric current line, an electron discharge device, a second electron discharge device, means for connecting said discharge devices with said line, a second electric current line, means for operatively connecting said devices serially across
40 the second said line to cause impression of voltage thereon, means controlling the second said discharge device and operable to cause the voltage impressed on the second said line by the second said discharge device to oppose the voltage impressed thereon by the first said discharge device, and means controlling the last said means and operative to regulate and reverse the voltage impressed on the second said line by the second said discharge device.

50 9. In an electric current converting system, an electric current line, an electron discharge device, a second electron discharge device, means for connecting said discharge devices with said line, a second electric current line, means for
55 operatively connecting said devices serially across the second said line to cause transfer of energy from the first said line to the second said line, means controlling the second said discharge device and operable to cause transfer of energy
60 therethrough from the second said line to the first said line, and means responsive to abnormal conditions in the system and controlling the operation of the second said discharge device to cause interruption of the flow of current between
65 said lines.

65 said lines.

10. In an electric current rectifying system, an alternating current line, an electron discharge device, a second electron discharge device having an anode associated with a control electrode and
70 a cathode, means for connecting said discharge devices with said line, a direct current line, means for operatively connecting said discharge devices serially across said direct current line and operative to cause supply of current from
75 said alternating current line to said direct cur-

rent line, and means controlling said control electrode and operable to cause transfer of energy from said direct current line back to said alternating current line through the second said discharge device.

11. In an electric current rectifying system, an alternating current line, an electron discharge device, a second electron discharge device having an anode associated with a control electrode and a cathode, means for connecting said discharge devices with said line, a direct current line, means for operatively connecting said discharge devices serially across said direct current line and operative to cause supply of current from said alternating current line to said direct current line, means controlling said control electrode and operable to cause transfer of energy from said direct current line back to said alternating current line through the second said discharge device, and means controlling the last 20 said means to regulate the flow of energy through the second said discharge device. 15

12. In an electric current rectifying system, an alternating current line, an electron discharge device, a second electron discharge device having an anode associated with a control electrode and a cathode, means for connecting said discharge devices with said line, a direct current line, means for operatively connecting said discharge devices serially across said direct current line and operative to cause supply of current from said alternating current line to said direct current line, means controlling said control electrode and operable to cause transfer of energy from said direct current line back to said alternating current line through the second said discharge device, and means controlling the last said means to cause reversal of the flow of energy through the second said discharge device.

13. In an electric current rectifying system, an alternating current line, an electron discharge device, a second electron discharge device having an anode associated with a control electrode and a cathode, means for connecting said discharge devices with said line, a direct current line, means for operatively connecting said discharge devices serially across said direct current line and operative to cause supply of current from said alternating current line to said direct current line, means controlling said control electrode and operable to cause transfer of energy from said direct current line back to said alternating current line through the second said discharge device, and means controlling the last said means to regulate and reverse the flow of energy through the second said discharge device. 40 45 50 55

14. In an electric current rectifying system, an alternating current line, an electron discharge device, a second electron discharge device having an anode associated with a control electrode and a cathode, means for connecting said discharge devices with said line, a direct current line, means for operatively connecting said discharge devices serially across said direct current line and operative to cause supply of current from said alternating current line to said direct current line, and means controlling said control electrode and operable to cause the voltage impressed on said direct current line by the second said discharge device to oppose the voltage impressed thereon by the first said discharge device. 60 65 70

15. In an electric current rectifying system, an alternating current line, an electron discharge device, a second electron discharge device having an anode associated with a control electrode 75

- and a cathode, means for connecting said discharge devices with said line, a direct current line, means for operatively connecting said discharge devices serially across said direct current line and operative to cause supply of current from said alternating current line to said direct current line, means controlling said control electrode and operable to cause the voltage impressed on said direct current line by the second said discharge device to oppose the voltage impressed thereon by the first said discharge device, and means controlling the last said means to regulate the voltage impressed on said direct current line by the second said discharge device.
15. 16. In an electric current rectifying system, an alternating current line, an electron discharge device, a second electron discharge device having an anode associated with a control electrode and a cathode, means for connecting said discharge devices with said line, a direct current line, means for operatively connecting said discharge devices serially across said direct current line and operative to cause supply of current from said alternating current line to said direct current line, means controlling said control electrode and operable to cause the voltage impressed on said direct current line by the second said discharge device to oppose the voltage impressed thereon by the first said discharge device, and means controlling the last said means to cause reversal of the voltage impressed on said direct current line by the second said discharge device.
17. In an electric current rectifying system, an alternating current line, an electron discharge device, a second electron discharge device having an anode associated with a control electrode and a cathode, means for connecting said discharge devices with said line, a direct current line, means for operatively connecting said discharge devices serially across said direct current line and operative to cause supply of current from said alternating current line to said direct current line, means controlling said control electrode and operable to cause the voltage impressed on said direct current line by the second said discharge device to oppose the voltage impressed thereon by the first said discharge device, and means responsive to abnormal conditions in the system controlling said control electrode to cause interruption of the flow of current between said lines.
18. In an electric current rectifying system, an alternating current line, an electron discharge device, a second electron discharge device having an anode associated with a control electrode and a cathode, means for connecting said discharge devices with said line, a direct current line, means for operatively connecting said discharge devices serially across said direct current line and operative to cause supply of current from said alternating current line to said direct current line, means controlling said control electrode and operable to cause the voltage impressed on said direct current line by the second said discharge device to oppose the voltage impressed thereon by the first said discharge device, and means responsive to abnormal conditions in the system controlling said control electrode to cause interruption of the flow of current between said lines.
19. In an electric current rectifying system, an alternating current line, an electron discharge device, a second electron discharge device having an anode associated with a control electrode and a cathode, means for connecting said discharge devices with said line, a direct current line, means for operatively connecting said discharge devices serially across said direct current line and operative to cause supply of current from said alternating current line to said direct current line, means controlling said control electrode and operable to cause the voltage impressed on said direct current line by the second said discharge device to oppose the voltage impressed thereon by the first said discharge device, and means responsive to flow of excessive current between said lines to cause said control electrode to become constantly negatively energized with respect to said cathode to cause interruption of the flow of current through both said discharge devices.
